UNITED STATES PATENT OFFICE.

EDWARD A. TEEPELL, OF GERMANTOWN, PENNSYLVANIA.

CLEANING DEVICE.

1,303,414.

Specification of Letters Patent. Patented May 13, 1919.

Application filed October 8, 1912, Serial No. 724,548. Renewed October 4, 1918. Serial No. 256,914.

To all whom it may concern:

Be it known that I, EDWARD A. TEEPELL, residing at Germantown, county of Philadelphia, State of Pennsylvania, have invented a new and useful Cleaning Device, of which the following is a specification.

My invention relates to improvements in cleaning devices and comprises a flexible metallic fabric with means for normally maintaining the fabric in the smooth or flat position. Such a device is especially adapted for removing the carbon from the cylinders and piston heads of internal combustion engines.

Referring to the drawings, which illustrate merely by way of example, a preferable form of suitable means for effecting the object of my invention—

Figure 1 is a plan view.

Fig. 2 is a fragmentary view in part section of an engine cylinder and piston with my cleaning device shown in elevation.

Similar numerals refer to similar parts throughout the several views.

A suitable flexible fabric is formed by a series of interengaging rings or links 3, arranged to form a surface having a substantially circular margin or periphery. This ring consists preferably of a helical spring 4, having its opposite ends secured together. A resilient ring corresponding to the circular periphery of the fabric is thus provided. A number of the marginal rings or links 3 are engaged at separated points with a portion 5 or portions 6 of the extension of said helical spring. The purpose of the ring 4 is to maintain the fabric formed of the rings or links 3 in the flat or stretched out position, since the tendency of the ring 4 is always to maintain a circular shape.

When this swab or fabric with its marginal or surrounding ring or selvage 4 is used for cleaning the cylinder of an internal combustion engine it is preferably made to fit approximately the top of the piston of

such cylinder, so that the margin 4 will engage the sides of the cylinder as the piston reciprocates. The tension of the ring 4 prevents the links or rings 3 of the fabric from bunching, and thus prevents the fabric from balling or forming into a heap, which would occupy more space than is left between the top of the piston and the cylinder head. That is to say, the fabric is always held out approximately flat, so that, as it is thrown between the top of the piston and the cylinder head, it always maintains its flat position or approximately such position and efficiently cleans the carbon from the interior surfaces of the cylinder and the top of the piston, without danger of injury thereto.

What I claim is:—

1. A cleaning device adapted for use within an engine cylinder, comprising a flexible metallic body portion having a circular contour when flat and resilient means for normally maintaining said circular contour.

2. A cleaning device for cylinders of internal combustion engines comprising a plurality of interconnecting metallic links forming a fabric having a circular contour when flat, corresponding to the interior cross-section of the cylinder, and an annular spring engaged by marginal links of the fabric and adapted to maintain the fabric normally flat under tension of the spring.

3. A cleaning device for engine cylinders and pistons comprising a plurality of interconnecting metallic links forming a flexible fabric having an approximately circular margin when flat, a helical spring engaging the marginal links of the fabric to maintain the fabric normally flat, said device adapted to lie upon the top of the piston and to be reciprocated between the piston and the cylinder head for the purpose specified.

EDWARD A. TEEPELL.
